UNITED STATES PATENT OFFICE.

THOMAS B. WOODS AND CHARLES E. WILLIAMS, OF HEADLAND, ALABAMA.

ROW-MARKER.

1,025,040.

Specification of Letters Patent.

Patented Apr. 30, 1912.

Application filed May 9, 1911. Serial No. 625,985.

To all whom it may concern:

Be it known that we, THOMAS B. Woods and CHARLES E. WILLIAMS, citizens of the United States, residing at Headland, in the 5 county of Henry and State of Alabama, have invented new and useful Improvements in Row-Markers, of which the following is a specification.

The invention relates to row markers, and 10 has for its primary object to provide a row marker which is exceedingly simple and inexpensive, and that may be mounted upon the beam of a plow, whereby it may be swung to either side thereof, thus enabling 15 the marking of the ground, so as to indicate the distance or width between the furrows.

Another object of the invention is the provision of a marker of this character in which the marking device may be adjusted laterally relative to the plow beam, thus enabling 20 the marking of the ground, whereby furrows may be formed at different distances apart.

A further object of the invention is the 25 provision of a row marker of this character which may be readily and conveniently attached to and detached from the beam of a plow, and also capable of adjustment for measuring the distance between the furrows, 30 when the plow is in operation.

In connection with a device of this construction, the invention has for a further object to provide a novel construction, combination and arrangement of parts, the details of which will appear in the course of 35 the following description, in which reference is had to the accompanying drawings forming a part of the specification by like characters of reference, designating similar 40 parts throughout the several views, wherein:

Figure 1 is a fragmentary perspective view of a plow beam, showing the invention applied thereto and in position for marking the ground. Fig. 2 is a horizontal longitudinal sectional view through the inner tubular section of the supporting arm of the 45 marker. Fig. 3 is a sectional view on the line 3—3 of Fig. 2.

Similar reference characters indicate corresponding parts throughout the several views of the drawings.

Referring to the drawings by numerals, 5 designates a portion of the draft beam of a plow, which is of the ordinary well-known 55 construction, and on which is mounted the

reversible and adjustable row marker, as will be hereinafter more fully described.

The row marker comprises a supporting plate or base 6, the same being superimposed upon the top face of the plow beam 5, at the required point thereof, and is clamped thereto by means of clips 7 which are adapted to embrace the plow beam for the fastening of the supporting plate or base thereon, the latter being provided with upturned bearing 60 ears 8, in which is swingingly connected the marker arm, presently described.

The marker arm comprises an inner tubular section 9 provided at its inner end with an elbow 10, in which is fixed a pivot pin 70 11 journaled in the bearing ears 8 and formed integral with a forwardly converging brace extension 12, the latter being formed with an eye terminal 13, bent in a forward direction to lie against and in 75 alinement with the outer end of the inner tubular section 9, and through which is passed an outer adjustable or extensible section 14, the latter being telescoped within the inner tubular section 9, so as to lie at 80 right angles to the beam 5 of the plow and to project laterally therefrom, when swung to either side of the line of draft of the said plow.

Mounted on the outer end of the extensible or adjustable section 14 is a land marking head, comprising a T-shaped coupling 85 15, the same being threaded upon the outer end of the said section 14 and carries oppositely extending forwardly bowed marking 90 fingers or tines 16, the ends of which are directed rearwardly, so that upon the swinging of the marking arm at opposite sides of the beam 5, one of the marking fingers or tines 16 will contact with the ground, so 95 that as the plow is advanced a line will be indicated in the ground for determining the location of the formation of the next furrow adjacent to the one previously formed. The outer section 14 carrying the marking 100 head is locked within the inner section 9 by means of a set screw 18, threaded in the inner section 9, near the outer end thereof.

It is clearly obvious that the marking device may be attached to other types of agricultural implements or machines, and requires no alteration in the construction of such machines or said marking device for application thereto. Also, it will be seen 105 that the marking arm may be extended or 110

shortened, so that the furrows may be laid out at different distances apart, the marking device being capable of being shifted from one side to the other of the draft beam 5 of the plow, for convenience in the execution of plow work in a field, as will be obvious.

From the foregoing, taken in connection with the accompanying drawings, it is 10 thought that the construction, and operation of the invention will be readily understood, without requiring a more extended explanation, and therefore the same has been omitted.

15 What is claimed is:

The combination with a draft beam, of a row marking attachment, comprising a supporting plate adapted for horizontal and detachable connection with the draft beam 20 and having upturned perforated ear terminals, an inner tubular section extending at

right angles to said plate, an outer tubular section slidably engaged in the inner tubular section, an elbow union on the inner end of said inner tubular section, a brace rod 25 disposed rearwardly of the inner tubular section and having an eye section at its outer end for engaging the outer end of said inner tubular section, the inner end of said brace rod being bent at an angle upon itself 30 and passing through said ear terminals to form a pivot portion, the inner extremity of said rod engaging said union, and means for adjustably clamping said plate upon said draft beam. 35

In testimony whereof we affix our signatures in presence of two witnesses.

THOMAS B. WOODS.
CHAS. E. WILLIAMS.
